INSULATOR

Albert D. Martin, Jr., Philadelphia, Pa.

Application October 18, 1945, Serial No. 623,159

1 Claim. (Cl. 174—175)

(Granted under the act of March 3, 1883, as
amended April 30, 1928; 370 O. G. 757)

1

The invention described herein may be manufactured and used by or for the Government for governmental purposes, without the payment of any royalty thereon.

This invention relates to insulators and more particularly to insulators for supporting wires.

The primary object of this invention is to provide an insulator that may be installed or replaced on a completed line without the necessity of passing ends of the wire through the insulator.

Another object of this invention is to provide an insulator for accurately spacing transmission lines of a radio set.

Still another object of this invention is to provide an insulator that may be quickly installed.

Still another object of the invention is to provide an insulator which is simple to construct, yet holds the wire securely.

Briefly, the invention comprises an insulating body composed of any suitable insulating material which has a plurality of slots. The configuration of these slots is such that wire may be tightly inserted therein. The configuration in question is shown in the drawings.

Fig. 1 illustrates a top view of the insulator constituting my invention.

Fig. 2 is a front view of an insulator embodying my invention.

Fig. 3 is an end view of the insulator of Figs. 1 and 2.

Fig. 4 is a perspective view of an insulator built in conformity with the invention.

Fig. 5 is an enlarged fragmentary section on the line 5—5 of Fig. 2.

Fig. 6 is a greatly enlarged section on the lines 6—6 of Figs. 3 and 5.

My invention is embodied in an insulating body 10 of any suitable material which has a central hole 11 therethrough. The hole 11 is provided for the purpose of bolting or screwing the insulator to a suitable pole, post, tree, etc. For example, if the insulator is to be mounted on the cross arm of a telephone pole, it should be placed with the hole 11 in a vertical position above the top face of the cross arm of the pole and a screw or bolt would extend vertically through the hole 11 into the post. Four slots are to be found in the insulating body 10, namely, slots 12, 13, 14 and 15. Each of these slots has substantially the same configuration which is such that when a wire is placed in a slot in a proper fashion, it will be securely retained therein.

Except for the width of the slot, the configuration of a slot may be visualized if it is assumed

that a wire such as 16 positioned at a 60 degree angle and to one side of Fig. 4 is moved directly to the left to point 19 at which time it is turned in a vertical plane to a horizontal position 17.

5 Each of the slots 12, 13, 14 and 15 has a restricted upper portion 18 into which the wire may be forced after it is positioned in the slot.

The body of the insulator is elongated along the axis of the hole 11 and its transverse dimension externally is sufficient to provide a minimum wall thickness around this hole sufficient to afford the desired structural strength for the uses contemplated. On two sides of this body opposite radial enlargements or ribs 10a and 10b are

15 formed extending throughout its length. These enlargements then constitute respective ends of the insulator, and the body thus has a major plane on the axis of the hole 11 medially of the thickness of the ribs, and a minor plane through

20 the hole at right angles to the major plane. The slots are formed through these ribs, extending across the end faces (as in Fig. 3) from front to rear. The main or outer and entrance portion of each slot is a deep part 20 having parallel

25 planiform sides spaced apart considerably more than the diameter of the wire to be mounted, and all inclined downwardly from the rear toward the front at an angle of approximately sixty degrees to the major plane of the insulator. The

30 planes of the sides of these slots is normal to said minor plane of the insulator, although these angles may be varied as found desirable. In the present instance the slots at one end are aligned with respective slots at the opposite ends, although this is not essential in all cases, depending

35 on the nature of the wiring to be mounted. It is desirable in the principal situations where the device is useful, however, for the planes of the outer parts of the slots to be inclined at the same angle to the major plane. This permits

40 the insulator to be tilted between two pairs of wires, for instance, so that all four may be pressed in through the slot parts 20, and the insulator then erected to thereby secure all the wires at

45 one time, and the insulator then secured upon a cross arm or other support. As a result, it is a highly important benefit of the invention that replacement of broken insulators on lines already strung may be effected without increasing the

50 tension of the wires, and the form of the slots is such that this may be done without introducing bends that might weaken the wire, as will appear.

By the arrangement of the slot parts 20 as described, it will be seen that all have an upper

55 end at the "back" of the insulator and a lower

end at the front, shown in Fig. 2. The terms "ends," "front" and "back" are applied solely for convenience in description and there is no utilitarian effect dependent thereon.

Each slot 12 to 15 has at its lower end at its extreme inner limit an upward extension or slot 21 with parallel vertical sides the clearance between which is the same as that between the upper and lower sides of the part 20; and at the upper end each part 20 has a downward extension or slot 22 similar to the one 21 except for its direction, and in the same plane. The extensions 21 and 22 both have a horizontal termination consisting of identical restricted portions 18-18', respectively, constituting seats which are formed by an abrupt narrowing of the slot so that it will accommodate against the ends of the extensions the horizontal wire to be supported, as before mentioned. It should be noted that the upward extension 21 has its limit or seat 18 slightly above the limit of the downward extension 22, as indicated by the dotted lines in Fig. 3. By the abrupt narrowing of the slots there are formed angular shoulders 23, at respective sides of each restricted portion 18. It may also be appreciated that by continuing the extensions 21 and 22 beyond a mean horizontal line, a straight clearway is formed entirely through the insulator (see Fig. 2), so that an engaged straight wire may lie commonly at the limits of the extensions 21 and 22 without change of its axial direction (see 17, Fig. 4). As may be understood from Fig. 2, the axis of a geometrical projection of the limiting surfaces of the two restricted parts or seats 18-18' may closely correspond to the axis of a straight wire, laid against the seats as shown at 17 in Fig. 4.

By reason of the relation of the extensions 21 and 22 to the parts 20 of the slots 12 to 15, it will be apparent that each extension, between its seat and the opposed side of the part 20, is V-shaped, one side of the V being the inclined side of the part 21, and the other side of the V being the horizontal termination 18 or 18' of the extension 21 or 22, as the case may be. These extensions, for the purpose of considering their operative relation to the engaged wire, and for descriptive convenience, may be regarded as separate coplanar oppositely located V-shaped slots, with their convergent parts in conjunction, and the part 20 may be regarded as a lateral third slot mutually joining the two. By the opposition of the slot portions 21 and 22, in conjunction as shown, the sides of the V-shaped portions do not converge to a point, but stop short of each other, as in Fig. 5, and form a throat space 25 or connecting slot.

By this arrangement, when a wire is fully positioned in the insulator, it will be supported in the seat 18' at its lower side from a point a little to the right of the major plane (of the insulator) to the rear face of the rib 10a or 10b; and at its upper side will be confined in the slot 21 over a distance beginning a little to the left of the major plane and extending to the front of the rib. In the case of a wire with insulation thereon, the shoulders 23 will serve to cut through or into the insulation when the wire is forced into the restricted parts 18-18'.

In order to install the wire after the insulator

has been bolted to the cross arm of a post, the wire 16 is moved to the left into the slot until it reaches the vertical portion of the slot at which time it is turned and forced into the restricted area at the top of the slot. This causes the bare wire to be retained securely. When four wires are respectively in slots 12, 13, 14 and 15 their relative position is insured. It is noted that at the center of the slot through which wire 16 is shown as passing there is a restricted area 25 (indicated by dotted lines in Fig. 3), where the wire is confined at its upper and lower sides by the longitudinally spaced inner terminations of the seats 18-18' respectively, which necessarily terminate at the inclined surfaces of the slot 20.

I claim to have invented:

An insulator for supporting wire comprising an insulating body constructed to be mounted in a fixed relation to the direction of a wire to be supported and having two generally planiform and coplanar and generally V-shaped slots opening on opposite sides of said body at their larger ends, each slot having two vertical parallel sides and two sides converging toward a central point but stopping short of each other, the included space within the slots extending across a geometrical horizontal line through the slots, one of the converging sides in each slot being shaped to form a transversely restricted part and to constitute a wire seat, the said seat of one slot being parallel to and below said line, the seat of the other slot being parallel to and above said line, said restricted parts and seats being spaced from said line so that a hole is formed through said body the vertical dimension of which between the levels of the extremes of said seats constitutes a wire-receiving space, and whereby the restricted parts and seats of the slots will each fit snugly partly around a supported straight wire, the seats engaging upper and lower sides of such wire at longitudinally spaced parts of the wire, the major parts of the slots being substantially wider than said seats, that one of the convergent sides in each slot which is opposite said seat therein being inclined, the said inclined sides being parallel to and at opposite sides of a common plane, said body having also a substantially planiform slot opening laterally from the first named slots through a side of the said body and of a width equal to that of the wider parts of the first named slots, its sides being coincident with respective said inclined sides of the first named slots, angular shoulders parallel to said line being formed on respective sides of said restricted part of each of the first named slots at the junction of the said wider parts of the first named slots and the said restricted parts of the slots.
